ATTORNEY'S

UNITED STATES PATENT OFFICE.

FRANK L. PETRINI, OF NEW YORK, N. Y.

DESIGN FOR A STAMPED HAT-LINING.

SPECIFICATION forming part of Design No. 13,162, dated August 8, 1882.

Application filed June 29, 1882. Term of patent 7 years.

To all whom it may concern:

Be it known that I, FRANK L. PETRINI, a citizen of the United States, residing at New York, in the county and State of New York, 5 have invented and produced a new and original Design for a Stamped Hat-Lining, of which the following is a specification.

This design is applied to stamped or pressed linings for hats and caps; and it consists of 10 transverse vanishing corrugations at the junction of the top and side of the article, serving to imitate plaits or folds.

In the accompanying drawings, Figure 1 is a vertical section, and Fig. 2 an inverted plan 15 view, of the lining. Fig. 3 is a sectional view of the corrugations.

Similar letters indicate corresponding parts.

The letter A designates the body of the lining, formed of a fibrous or textile material, 20 which is stiffened and stamped or pressed into shape; and B indicates the corrugations. These corrugations extend transversely to the lining, side by side with each other, and intersect the

plane of the junction of the top and side of the article, each corrugation vanishing at both 25 ends, having an elliptic lanceolate shape in the direction of length and having an angular base. The object and effect of the corrugations is to imitate the plaits or folds of an ordinary lining, and to this end they may extend either in a perpendicular or an inclined plane. 30

What I claim as new, and desire to secure by Letters Patent, is—

The design for a stamped hat-lining, consisting of transverse vanishing corrugations 35 at the junction of the top and side of the article, as shown and described.

In testimony whereof I have hereunto set my hand and seal in the presence of two subscribing witnesses. 40

FRANK L. PETRINI. [L. S.]
